UNITED STATES PATENT OFFICE

FRED E. HUNT AND CHARLES LOUIS PETERS, OF MARINETTE, WISCONSIN

MULTIPLE BULLETIN BOARD

Application filed October 8, 1923, Serial No. 311,108. Renewed February 26, 1931.

This invention relates to multiple bulletin boards.

Objects of this invention are to provide a novel form of bulletin board which is so constructed that it may hold any number of bulletin boards, which may be used on both sides and may be swung to any desired position and rotated about an axis through the bulletin board to any desired angle.

Further objects are to provide a construction which is very simple and which is easy to produce.

An embodiment of the invention is shown in the accompanying drawings in which:

Figure 1 is a side elevation of the device with parts in section;

Figure 2 is a transverse sectional view on the line 2—2 of Figure 1.

Referring to the drawings, it will be seen that the device comprises a central main supporting standard 1 which is provided with a bottom flange 2 and with an upper bracket 3 integral with an upper flange 4. The flange 2 may be secured to the floor and the flange 4 may be secured to a vertical wall.

A plurality of bulletin boards 5 are employed and are each provided with upper and lower brackets 6 which are equipped with trunnions 7. The trunnions are carried within the fittings 8 at the ends of arms 9. The arms have their inner ends rigidly secured to the relatively heavy bearings 10 which are journaled upon the vertical standard or rod 1.

Each of these bearings is independently supported by means of a collar 11 provided with a set screw, as indicated in Figure 1.

The bulletin boards are preferably mounted in a staggered relation, that is to say, with one projecting below the bottom of the succeeding board.

Further, it is to be noted that the arms 9 are longer than half the width of the bulletin board supported thereby. This permits the turning of the bulletin boards at any desired angle about axes passing therethrough.

In addition to this, the bulletin boards may display either side and may receive any suitable data pinned, tacked, or otherwise attached thereto. They may be swung about the rod 1, as indicated in the drawings.

Further, they may be turned flat and stacked against the wall when not in use.

It will be seen that a very simple type of multiple bulletin board has been provided by this invention which is easy to construct, which is cheap, and which is eminently practical.

Although the invention has been described in considerable detail, such description is intended as illustrative rather than limiting as the invention may be variously embodied and as the scope of such invention is to be determined as claimed.

We claim:

1. A multiple bulletin board comprising a vertical standard having a supporting flange at its bottom and having a laterally disposed flange at its top, whereby it may be attached to the floor, and a wall of a room, a plurality of bearing members journaled upon said standard, collars supporting said bearing members, a plurality of rods extending outwardly from said bearing members, and bulletin boards pivotally supported at the outer ends of said rods.

2. A multiple bulletin board comprising a vertical standard, means for supporting said standard, a plurality of bearing members carried by said standard, collars rigidly attached to said standard and supporting said bearing members, a plurality of rods extending outwardly from said bearing members, said rods each having an outer bearing member at its outer end, a plurality of bulletin boards, said bulletin boards each having brackets secured thereto provided with trunnions fitting within the outer bearing members of said rods.

In testimony that we claim the foregoing we have hereunto set our hands at Marinette, in the county of Marinette and State of Wisconsin.

FRED E. HUNT.
CHARLES LOUIS PETERS.
